BUILDING WALL

Luther S. Munson, West Riverdale, Md., assignor
to Munleek Engineering Company, Washington,
D. C., a corporation

Application April 11, 1933, Serial No. 665,578

6 Claims. (Cl. 72—41)

In the present invention I provide a building wall and tile or block therefor, designed as an improvement over my prior patents in this art, especially Reissue Patent No. 17,291, reissued May 5 7th, 1929.

With the rising cost of building materials, especially masonry walls, the savings in materials as well as labor become of increasing importance. In addition, the regulatory building codes set up 10 many requirements for the construction of walls. In this art therefore, consideration must be given to the cost of manufacturing the building materials, the labor necessary for the erection of the wall, and the requirements of the building codes. 15 In my invention herein shown and described, I employ in the wall a minimum amount of materials and so construct the wall units to permit the erection of the wall in a minimum period of time; by reason of the pre-formed character of 20 the tiles or blocks, erection of the wall by workmen unskilled in the art is entirely feasible.

Other objects of the invention are to provide a wall which is not entirely dependent on the mortar bond for lateral stability and which will 25 not fail under loads and conditions incident to the building's occupancy, because of the bonded and almost monolithic character of the wall; to provide a wall which will resist moisture penetration, in that capillary action through the wall is 30 impossible; and to provide a wall of inherent stability, incapable of premature collapse under fire or exposure to storm conditions, and capable of discharging the functions of support and heat insulation to prevent undue fire loss, thereby 35 complying with all the requirements of the building codes.

A further object of the invention is to provide building blocks designed to permit use thereof, especially in miniature, as toy building blocks for 40 the erection of toy houses, garages, etc.

Other objects will be apparent from the following description of the present preferred form of the invention, taken in connection with the accompanying drawings, wherein

45 Fig. 1 is a detail fragmentary, perspective view of a wall constructed in accordance with the present invention, portions thereof being broken away to disclose details of the wall;

50 Fig. 2 is an end elevational view of a wall constructed in accordance with the present invention and illustrating to advantage the manner of arranging the foundation tile elements with an adapted block interposed therebetween, and the wall superstructure tile elements;

55 Fig. 3 is an end elevational view of superstruc-

ture tile elements of the present invention, with an adapted block associated therewith; and

Fig. 4 is a perspective view of a tile element constructed in accordance with the present invention.

In making a wall in accordance with the teaching of the present invention, I prefer to employ tile elements 5 as standard units in the construction of the foundation or base of the wall, and standard units 6 composed of tile elements in 10 the wall superstructure, said foundation tile elements and superstructure elements being connected at the corners and around door and window frames, by adapter blocks, generally designated 7. It will be noted that the tile elements 15 5 are identical in construction to the tile elements 6, the former being larger for use in a twelve-inch wall and the latter being adapted for use in an eight-inch wall. Each of the elements 5 and 6, as shown to advantage in Fig. 4, 20 consists of a rectangular body, one face of which is provided with a hollow rib or protrusion 8, while the opposite face is provided with a groove or recess 9 which extends in parallel relation to the protrusion. Each of the tile elements 6 is 25 provided with an opening 10 on each side of the protrusion or rib 8, while each of the tile elements 5, as shown to advantage in Fig. 2, is provided with two openings 11, on each side of its protrusion or rib 8. Each of the openings 10 are 30 equal to one-quarter inch of commercial insulation to conform to regulatory building codes. It will be noted that each of the ribs or protrusions 8 has the opposite sides canted or converged toward the base thereof, as indicated at 35 12, to provide a finger grip for convenience in laying of the tiles, as shown to advantage in Fig. 2, and likewise to provide grooves which form habitats for mortar or other plastic material 13. The apex of each protrusion or rib has 40 the corners thereof bevelled, as indicated at 14, to complement the contour of the grooves or recesses 9 of the tiles. Manifestly in the manufacture of tiles, irregularities in the surfaces appear, so as to prevent a tight fit between adjacent tile elements. However, by beveling the apices of the protrusions or ribs, an accurate fit between superposed tiles is assured and the wall tiles are thus self-aligned. In laying the tiles 45 there is a complete absence of mortar between the protrusions or ribs 8 and their complementary recesses.

It will be noted that the opposite faces of the tiles 5 and 6 and block 7 are grooved, as indicated at 15, these grooves being preferably dovetail in 55

shape to key in the plastic material 13 interposed in the horizontal spaces between the tiles 5 and 6 on the opposite sides of the protrusions or ribs 8. The grooving of the tiles and blocks, in addition to the canting of the sides of the protrusions 8, prevents displacement or disintegration of the mortar or plastic material 13.

In building up a wall in accordance with the present invention, the tiles 5 are employed in the foundation of the wall for as many courses as is deemed essential to support the load to be imposed thereon under varying conditions. As shown in Fig. 1 of the drawings, the tiles 5 will be built up in staggered relation and when so arranged, prevent the penetration of moisture therethrough and likewise prevent capillary action in that the line of plastic material is interrupted by the protrusions or ribs 8, which enter the complementary recesses in the adjacent or contiguous tiles or blocks. To finish off the corners it is necessary to use adapter blocks, as I have indicated at 7, and also finishing blocks or bricks 16. Upon reference to Fig. 1 of the drawings, it will be noted that one of the standard unit tiles 5 has the protrusion or rib thereof projected into a recess in the bottom of a superposed adapter block 7. The adapter block projects over beyond the end of the tile 5 in order that a portion of the recess of the adapter block 7 is unoccupied and may be filled in with plastic material. At the end of the adapter block, the brick 16 is mounted to finish the corner. It will be noted that in Fig. 1 for the purpose of carrying out the architectural plan usually employed in buildings constructed of brick, I have shown five courses simulating stretcher brick on the outside and a superimposed course simulating header bricks. Obviously, this is unnecessary in the present invention in that standard units may be used throughout the entire wall except in the corners of the latter and around window frames, but I prefer to show the feasibility of using the tiles of the present invention in this manner if and when desired. As is apparent, the standard units used as headers are formed by cutting standard units in half.

By use of the present block it becomes apparent that when the standard units are built up in the wall, as set out herein, moisture cannot find its way therethrough because capillary action which may take place through the mortar or other plastic material used, is interrupted by the protrusions or ribs 8. At the corners where the adapter blocks 7 and bricks 16 are used, it is apparent that capillary action is likewise interrupted because of the portion of the standard units directly in the path of travel of mortar between the adapter blocks. By employing the twelve-inch blocks in the foundation of the wall, a ledge 17 is provided, as shown in Fig. 2 of the drawings, adapted for the reception of beams, etc.

It is to be understood that with the present block furring of the wall, use of face bricks, back-up walls, etc., are entirely eliminated. The wall is complete in itself and satisfies all requirements for insulation and water-proofing, with proper regard for sanitation. The peculiar

construction of the protrusions or ribs greatly facilitates the handling of the tiles, insures absolute accuracy in the laying of the tiles, and prevents passage of moisture through the wall between the standard units.

Although I have herein described the present preferred form of my invention, various changes may be made therein, within the scope of the appended claims.

What is claimed is:

1. A block for building walls consisting of a rectangular body equipped with a rib on one face thereof, the sides of said rib being canted and the corners thereof bevelled, the opposite face of said block having a recess therein parallel to said rib of a shape complementing the apex of the latter.

2. A building wall composed of standard tile elements, each of which is relatively flat and horizontally arranged in superposed relation, 20 each of the elements of one course being equipped with a rib projecting from one of the faces thereof, having its sides canted and the corners thereof bevelled, each element of the superposed contiguous course having a recess formed 25 in one of the faces thereof which complements the apices of the ribs of the subjacent course.

3. A building wall composed of a single tier of tile elements arranged in superimposed relation, said tile elements each having an upwardly 30 extending projection on the upper surface and a complementary recess in the lower surface, said projection extending into the recess super-adjacent tile and contacting the wall of the recess, whereby portions of the joints of contiguous tiles are rendered mortarless and incapable of capillary attraction.

4. A building wall composed of tile elements arranged in superimposed relation, said tile elements each having an outwardly extending projection on one face and a complementary recess on the opposite face, said projection extending into the recess of the adjacent tile and contacting the wall thereof, whereby a portion of each joint is rendered mortarless and incapable of 40 capillary attraction.

5. A building wall composed of tile elements each having longitudinal voids therein and each having a central longitudinal projection on one face and a longitudinal recess in the opposite face 50 for the reception of a projection of an adjacent tile, said recess being of less depth than the projection whereby spaces are provided between proximate faces of tile elements, and mortar in said spaces to form a joint interrupted by said projection.

6. A block for building walls including an enclosed block body with a centrally located protrusion on one face, said body and protrusion having voids therethrough, said block being channelled to provide a groove opposite the base of the protrusion for the reception of the outer portion of the protrusion of an adjacent block, whereby spaces are provided between the blocks 60 on opposite sides of the protrusion, and mortar in said spaces.

LUTHER S. MUNSON.
